UNITED STATES PATENT OFFICE.

GEORGE L. THOMPSON, OF CHICAGO, ILLINOIS.

DESIGN FOR A FRONT FORK FOR VELOCIPEDES.

SPECIFICATION forming part of Design No. 30,071, dated January 24, 1899.

Application filed December 27, 1898. Serial No. 700,459. Term of patent 7 years.

To all whom it may concern:

Be it known that I, GEORGE L. THOMPSON, of Chicago, in the county of Cook and State of Illinois, have invented and produced a new 5 and original Design for a Velocipede-Fork, of which the following is a specification.

My novel design consists in a front fork for velocipedes of that type having a fork-crown of oval or inverted-U shape, and the distinctive feature of novelty of the design consists 10 in the triangular formation of its side members, as shown in the accompanying drawings, in which—

Figure 1 is a side elevation of a velocipede-15 fork embodying my novel design. Fig. 2 is a front elevation thereof. Fig. 3 is a transverse section taken on line 3 3 of Fig. 1.

In the drawings, A designates the fork as a whole, A' its oval fork-crown, and A² its side 20 members. The latter are made triangular in

cross-section, as shown in Fig. 3, the apex a of the triangle being directed outwardly and the triangular formation extending, as shown, from the juncture a' of the fork-crown and side members nearly to the tips a² of the latter. Aside from this peculiarity the fork is of the usual appearance and need not be more particularly described.

I claim as my new and original design—

The design for a front fork of a velocipede, 30 substantially as herein shown and described.

In testimony that I claim the foregoing as my invention I affix my signature hereto, in the presence of two subscribing witnesses, this 21st day of December, A. D. 1898.

GEORGE L. THOMPSON.
